UNITED STATES PATENT OFFICE.

EDWIN NORTON, OF MAYWOOD, ILLINOIS, ASSIGNOR TO THE AUTOMATIC VACUUM CANNING COMPANY, OF CHICAGO, ILLINOIS.

VACUUM-SEALING KEY-OPENING PRESERVING-JAR.

SPECIFICATION forming part of Letters Patent No. 681,131, dated August 20, 1901.

Application filed November 3, 1900. Serial No. 35,319. (No model.)

To all whom it may concern:

Be it known that I, EDWIN NORTON, a citizen of the United States, residing in Maywood, in the county of Cook and State of Illinois, have invented a new and useful Improvement in Vacuum-Sealing Key-Opening Preserving-Jars, of which the following is a specification.

My invention relates to improvements in glass or earthenware jars for containing hermetically-sealed food and other products.

My invention consists in the combination, with a glass or earthenware jar having an external shoulder on its neck or top, of a sheet-metal sealing-ring having an internal shoulder and hermetically sealed and secured to the jar and provided with a key-opening tongued tearing-strip and a sheet-metal cover hermetically sealed and secured to the sealing-ring.

It further consists in a glass or earthenware jar provided with an external shoulder at its neck or top, in combination with a sheet-metal sealing-ring provided with an internal shoulder or upright fold resting on the shoulder of the jar, with a packing-ring between and secured to the jar by an inturned flange at its lower edge embracing the shoulder on the jar and compressing the packing, said sheet-metal sealing-ring being provided with a tongued tearing-strip above the shoulder on the jar and having also a roll or flange above the tearing-strip and a sheet-metal cover adapted to be sealed and secured to said sealing-ring by a vacuum or atmospheric pressure seal and additionally secured thereto by a mechanical lock or seam.

It further consists in the novel construction of parts and devices and in the novel combinations of parts and devices herein shown and described, and specified in the claims.

In the accompanying drawings, forming a part of this specification, I have shown a preserving-jar embodying my invention, and also the successive steps or stages of its manufacture and sealing.

In said drawings, Figure 1 shows the blank in the flat from which the sealing-ring is formed; Fig. 2, the sealing-ring formed from the blank; Fig. 3, the sealing-ring at its next stage or step provided with a wide-open internally-projecting bead; Fig. 4, the sealing-ring at its next step with the walls of the bead com-

pressed or folded together to form an internal fold or shoulder. Fig. 5 shows the sealing-ring at its next step after this internal fold has been turned into an upright position. Fig. 6 shows the sealing-ring at its next step provided with a flange or roll at its upper edge and hermetically sealed and secured to the neck or top of the glass jar by an inturned flange at its lower edge embracing the external shoulder on the glass jar and compressing the packing between the external shoulder on the jar and the internal shoulder on the sealing-ring. Fig. 7 shows the jar provided with the sheet-metal sealing-ring and with its sheet-metal cover resting loosely in place thereon and ready to be sealed or secured thereto by a vacuum or atmospheric-pressure seal when the filled jar is placed in the receiver of an air-pump, the air exhausted therefrom, and again suddenly restored. Fig. 8 shows the same after the jar has been removed from the receiver and the sheet-metal cover additionally locked and secured to the sealing-ring by a mechanical seal or seaming. Fig. 9 shows the jar after it has been opened by winding the tongued tearing-strip of the sealing-ring on a key and the jar ready to be again closed by the slip-cover formed by removing the tearing-strip from the sealing-ring. Fig. 10 is an enlarged elevation, partly in section, of the sealed jar; and Fig. 11 is a partial plan of the glass jar.

In the drawings similar letters of reference indicate like parts throughout all the figures.

In said drawings, A represents a glass or earthenware jar having its neck or top provided with an external shoulder a to receive a packing-ring a'.

B is the sheet-metal sealing-ring, the same being formed from a narrow rectangular blank B' and provided with a tongued tearing-strip b, marked off by scored or weakened lines b' b² and provided with a notch b⁴ at the side seam b⁵. After the sealing-ring B has been formed, as illustrated in Fig. 2, a wide internally-projecting bead b⁶ is formed therein, with its upper edge just below the lower score or weakened line b² of the tongued tearing-strip. The next step is to stamp or compress the walls of this bead b⁶ together, thus forming an internal fold b⁷ in the stock of the seaming-ring, as illustrated in Fig. 4, which at the next step, as illustrated in Fig. 5, is turned

into an upright position, thus forming an upright internal fold and producing a rigid shoulder b^8 , between which and the external shoulder a on the jar A a packing-ring a' may 5 be firmly compressed and held by turning or forming the inwardly-projecting flange b^9 at the lower edge of the seaming-ring. Before the sheet-metal seaming-ring is thus hermetically sealed and secured to the jar, as illustrated in Fig. 6, the seaming-ring is furnished with a roll, flange, or shoulder b^{10} at its upper edge to adapt the sheet-metal cover D to be hermetically sealed and secured thereto by a vacuum or atmospheric-pressure seal, 10 and also to be mechanically sealed, seamed, or locked thereto. The sheet-metal cover D has an annular groove or channel d formed by and between its inner and outer flanges d', d^2 , and which channel receives the packing d^3 , which in the sealing of the cover to the seaming-ring is compressed between the cover and the smooth shoulder b^{10} at the upper edge of the seaming-ring produced by the roll formed thereon. This enables the cover 15 to be hermetically sealed, locked, and secured to the jar and its seaming-ring by a vacuum or atmospheric-pressure seal by simply placing the jar after it has been filled in the receiver of an air-pump, with its cover 20 loosely in place thereon, as illustrated in Fig. 7, so that the air will be exhausted from the jar and then suddenly restoring air or other pressure to the receiver, and thus causing the cover to be forced home upon the seaming-ring by a straight downward movement, and thereby compressing the packing-ring d^3 25 and sealing the jar.

To prevent the contents of the filled jar from coming in contact with the sheet-metal 30 seaming-ring B or its cover D, protecting-disks C C' are inserted between the upper smooth flat face a^2 of the jar and the cover D. The lower one of these protecting-disks C is preferably of oiled or paraffined paper, and 35 thus made impervious, while the upper one C' is preferably a thicker and compressible board of paper or wood pulp.

After the cover D has been hermetically 40 sealed and secured thus to the jar and its seaming-ring by a vacuum or atmospheric pressure seal and the jar removed from the receiver of the air-pump the cover D is mechanically sealed, locked, secured, or seamed to the seaming-ring B, this being preferably 45 done by simply turning or crimping the lower edge d^4 of the outer flange d' of the cover D under the shoulder b^{10} , formed by the flange, turn, or roll at the upper edge of the seaming-ring, thus additionally compressing and holding 50 compressed the packing d^3 between the cover and the seaming-ring.

To open the jar, the tongued tearing-strip b is wound in the usual manner around the key F, provided for this purpose, thus leaving the 55 upright fold b^7 , with its smooth upper edge or surface, projecting above the lower torn edge produced by the removal of the tearing-strip,

thereby giving a perfectly smooth upper edge or mouth to the seaming-ring after the jar has been opened. The opening of the jar by 60 the removal of the tearing-strip also leaves the portion b^{11} of the seaming-ring above the upper score b' firmly attached to the cover D, thus forming a slip-cover flange therefor. This slip-cover flange portion b^{11} of the seaming-ring forms a tight and accurate fit with the upright fold b^7 . The upright fold b^7 has a slight inward curvature and a slight outward inclination at its upper part and a smooth beveled upper edge produced by the 65 fold in the stock, and as the slip-cover flange b^{11} has a slight inward inclination to its point of union with the cover D, produced by the action of the crimping-tools in turning the flange d^4 inward, the slip-cover is thus given 70 a very tight wedging fit on the seaming-ring, so that the jar may be closed practically airtight after it has once been opened.

As the internal upright fold has a curved or semitubular form in cross-section, it gives 75 great strength and stiffness to the seaming-ring at the point where the tearing-strip is detached therefrom, so that the tearing-strip will separate easily and uniformly and with certainty when it is wound upon the key in 80 opening the jar.

I claim—

1. The combined slip-cover and vacuum-sealing key-opening jar, consisting in the combination with a glass or earthenware jar A 85 having an external shoulder a at its neck, of a sheet-metal seaming-ring B, having a tongued tearing-strip b , and an internal upright fold b^7 projecting above the lower score of the tearing-strip, and provided with an in-turned flange b^9 at its lower edge securing the same to the jar, a sheet-metal cover D having inner and outer flanges d', d^2 , and an annular channel d between, furnished with a packing-ring d^3 , said seaming-ring having at its 90 upper edge a flange, turn or roll mechanically secured or united to said cover, and said seaming-ring having a slip-cover flange portion b^{11} projecting above the upper score of the tearing-strip and adapted to tightly fit, 95 when the tearing-strip is removed, said upright fold b^7 of the seaming-ring, substantially as specified.

2. The combination with a jar having an external shoulder at its neck, with a sheet-metal seaming-ring furnished with a tongued tearing-strip, and provided with an internal upright fold having a smooth upper edge projecting above the lower score of the tearing-strip, said seaming-ring having a flange at its 100 lower edge securing the same to the jar, and a slip-cover flange portion b^{11} projecting above the upper score of the tearing-strip, and a sheet-metal cover having a packing-ring and mechanically seamed or secured to said upper portion b^{11} of the seaming-ring, and forming, 105 when the tearing-strip is removed, a slip-cover fitting said upright fold b^7 of the seaming-ring, substantially as specified.

3. The combination with a jar having an external shoulder at its neck, of a seaming-ring furnished with a tongued tearing-strip and an internal shoulder, and provided with 5 an inturned flange at its lower edge securing the same to the jar, and with a flange or roll at its upper edge, of a sheet-metal cover having an annular groove and a packing-ring therein to adapt the same to be seamed and 10 secured to the seaming-ring by a vacuum or atmospheric-pressure seal, substantially as specified.
4. The combination with a jar having an external shoulder at its neck, of a seaming-ring furnished with a tongued tearing-strip and an internal shoulder, and provided with 15 an inturned flange at its lower edge securing the same to the jar, and with a flange or roll at its upper edge, of a sheet-metal cover having an annular groove and a packing-ring therein to adapt the same to be seamed and 20 secured to the seaming-ring by a vacuum or atmospheric-pressure seal, said cover having its outer flange mechanically seamed or 25 crimped to the flange or roll on the seaming-ring, substantially as specified.
5. The combination with a jar having an external shoulder at its neck, of a seaming-ring furnished with a tongued tearing-strip 30 and an internal shoulder, and provided with an inturned flange at its lower edge securing the same to the jar, and with a flange or roll at its upper edge, of a sheet-metal cover having an annular groove and a packing-ring 35 therein to adapt the same to be seamed and secured to the seaming-ring by a vacuum or atmospheric-pressure seal, said cover having its outer flange mechanically seamed or 40 crimped to the flange or roll on the seaming-ring, and said seaming-ring having a slip-cover flange portion b^{11} above the upper score of the tearing-strip and forming with the cover, when the tearing-strip is removed, a slip-cover fitting the portion of the seaming-ring attached to the jar, substantially as specified. 45
6. The combination with a glass or earthenware jar, of a cover and seaming-ring furnished with a tongued tearing-strip for opening the jar, said seaming-ring being hermetically sealed and secured to the jar, and said cover being hermetically sealed and secured to the seaming-ring, substantially as specified. 50
7. The combination with a jar having an external shoulder at its neck or top, of a sheet-metal ring having an internal shoulder and secured to said jar, and provided with a tongued tearing-strip above its internal shoulder, substantially as specified. 55
8. The combination with a jar having an external shoulder at its neck or top, of a sheet-metal ring having an internal shoulder and secured to said jar, provided with a tongued tearing-strip above its internal shoulder and 60 a packing-ring inserted between said seaming-ring and jar, substantially as specified. 65
9. The combination with a jar having an external shoulder at its neck or top, of a sheet-metal ring having an internal shoulder and secured to said jar, provided with a tongued tearing-strip above its internal shoulder and 65 a packing-ring having at its lower edge an inturned flange locking the same to the jar, substantially as specified. 70
10. The combination with a jar having an external shoulder at its neck or top, of a sheet-metal ring having an internal shoulder and secured to said jar, provided with a tongued tearing-strip above its internal shoulder and 75 a packing-ring inserted between said seaming-ring and jar, said sheet-metal ring having at its lower edge an inturned flange locking the same to the jar, substantially as specified. 80
11. The combination with a jar having an external shoulder at its neck or top, of a sheet-metal ring having an internal shoulder and secured to said jar, and provided with a tongued tearing-strip, said sheet-metal ring having a flange or roll at its upper edge, and 85 a sheet-metal cover having inner and outer flanges embracing said flange or roll on the upper edge of the ring, substantially as specified. 90
12. The combination with a jar having an external shoulder at its neck or top, of a sheet-metal ring having an internal shoulder and secured to said jar, and provided with a tongued tearing-strip, said sheet-metal ring having a flange or roll at its upper edge, and 95 a sheet-metal cover having inner and outer flanges embracing said flange or roll on the upper edge of the ring, and the outer flange on the cover being turned or crimped under the flange or roll at the upper edge of the 100 seaming-ring, substantially as specified. 105
13. The combination with a jar having an external shoulder at its neck or top, of a sheet-metal ring having an internal shoulder and secured to said jar, provided with a tongued tearing-strip said sheet-metal ring having at 110 its lower edge an inturned flange locking the same to the jar, said sheet-metal ring having a flange or roll at its upper edge, and a sheet-metal cover having inner and outer flanges 115 embracing said flange or roll on the upper edge of the ring, substantially as specified. 120
14. The combination with a jar having an external shoulder at its neck or top, of a sheet-metal ring having an internal shoulder and secured to said jar, provided with a tongued tearing-strip, a packing-ring inserted between 125 said seaming-ring and jar, said sheet-metal ring having a flange or roll at its upper edge, a sheet-metal cover having inner and outer flanges embracing said flange or roll on the upper edge of the ring, and the outer flange on the cover being turned or crimped under the flange or roll at the upper edge of the seaming-ring, substantially as specified.
